[57] CLAIM

The ornamental design for a dispenser for hot shaving lather, as shown and described.

DESCRIPTION

FIG. 1 is the front perspective view of a dispenser for hot shaving lather showing my new design;

FIG. 2 is a front elevational view of same;

FIG. 3 is a side elevational view of same, the side opposite being a mirror image thereof;

FIG. 4 is a rear elevational view of same;

FIG. 5 is a top plan view of same; and

FIG. 6 is a bottom plan view of same.

*Fig. 1.**Fig. 2.**Fig. 3.**Fig. 4.**Fig. 5.**Fig. 6.*
